UNITED STATES PATENT OFFICE

119,200

DESIGN FOR A FIRE DETECTING DEVICE

Stephen T. Van Houten, Allendale, N. J.

Application January 9, 1940, Serial No. 89,375

Term of patent 14 years

To all whom it may concern:

Be it known that I, Stephen T. Van Houten, a citizen of the United States residing at Allendale, in the county of Bergen and State of New Jersey, have invented a new, original, and ornamental Design for a Fire Detecting Device, of which the following is a specification, reference being had to the accompanying drawing, forming part thereof, in which:

Fig. 1 is a plan view of the fire detecting device, embodying the design of the invention.

Fig. 2 is a side elevation thereof.

I claim:

The ornamental design for a fire detecting device, as shown.

STEPHEN T. VAN HOUTEN.
